UNITED STATES PATENT OFFICE

106,104

DESIGN FOR A DESK OR SIMILAR ARTICLE

Albert Balster, Chicago, Ill.

Application July 21, 1937, Serial No. 70,544

Term of patent 7 years

To all whom it may concern:

Be it known that I, Albert Balster, a citizen of the United States, residing at Chicago, in the county of Cook and State of Illinois, have invented a new, original, and ornamental Design for a Desk or Similar Article, of which the following is a specification, reference being had to the accompanying drawing, forming a part thereof.

I claim:

The ornamental design for a desk or similar article substantially as shown.

ALBERT BALSTER.
